(Cl. D26—14)

To all whom it may concern:

Be it known that I, Carl L. Otto, a citizen of the United States residing at New York city, in the county and State of New York, have invented a new, original, and ornamental Design for a Sound Translating Machine, of which the following is a specification, reference being had to the accompanying drawing, forming a part thereof.

Figure 1 is a perspective view from a front corner showing the front, top and lefthand side of a sound translating machine, showing my new design.

Figure 2 is a rear elevational view thereof; and

Figure 3 is a righthand side elevational view thereof.

I claim:

The ornamental design for a sound translating machine, substantially as shown.

CARL L. OTTO.
